(57) **CLAIM**

The ornamental design for an outdoor-heater offset arm, as shown.

DESCRIPTION

FIG. 1 is a front elevational view of an outdoor-heater offset arm showing our new design;

FIG. 2 is a left-side-elevational view thereof;

FIG. 3 is a rear elevational view thereof;

FIG. 4 is a top plan view thereof; and,

FIG. 5 is a bottom plan view thereof. The broken line showing of other parts of an outdoor heater with offset arm are for illustrative purposes only and forms no part of the design.
